(57) **CLAIM**

The ornamental design for a filter for removing particle matter, as shown and described.

DESCRIPTION

FIG. 1 is a perspective view of a filter for removing particle matter illustrating our new design;

FIG. 2 is a front elevation view thereof;

FIG. 3 is a rear elevation view thereof;

FIG. 4 is a top plan view thereof, the bottom plan view thereof being a mirror image;

FIG. 5 is a right side elevational view thereof, the left side elevational view thereof being a mirror image;

FIG. 6 is an enlarged view delimited by the four lines labelled **6** in FIG. 2;

FIG. 7 is a cross-sectional view taken through line **7-7** of FIG. 2;

FIG. 8 is an enlarged cross-sectional view taken through line **8-8** of FIG. 6; and,

FIG. 9 is an enlarged view delimited by the four lines labelled **9** in FIG. 3.

The broken lines in the drawings represent unclaimed subject matter. The broken lines in FIG. 8 show truncation of length.
